FREDERICK KLEIN, OF COLLEGE POINT, AND FRED WALSLEBEN, OF OCEANSIDE, NEW YORK, ASSIGNEES TO WARP TWISTING-IN MACHINE COMPANY, OF BROOKLYN, NEW YORK, A CORPORATION OF NEW YORK

MECHANISM FOR KNOTTING TOGETHER THREADS

Application filed April 23, 1930. Serial No. 446,610.

This invention consists in certain improvements upon the method of and apparatus for tying weaver's knots (as in piecing a new warp onto a warp about to become exhausted in a loom) which is set forth in the Klein Patent No. 1,776,912. The principal object is to improve the method and apparatus therein set forth to the end that failure to form a knot or a possibility of collapse after discharge from the knot-forming procedure shall be avoided.

The invention will be set forth in reference to the accompanying drawings by which it is fully illustrated and wherein—

Fig. 1 is a front elevation of the apparatus; Fig. 2 is a front elevation of the first loop-former, the knot tyer, the second loop-former and certain parts concerned with our improvements, all in their retracted positions;

Fig. 3 is a somewhat similar view but showing the several parts more or less advanced in the operation of tying the knot;

Fig. 4 shows how the loops are formed in the two strands;

Fig. 5 shows in front elevation, partly in section, the second loop-former and a part of our improvements and mechanism for effecting their movement;

Fig. 6 is a fragmentary plan of what is shown in Fig. 5;

Fig. 7 shows in side elevation the means for gripping strand *a*;

Fig. 8 shows how the noose *a*² is formed around loop *b*' of strand *b* and the noose holder;

Fig. 9 is a right hand elevation, partly in section, of the means for forming loop *b*' in and severing and gripping and otherwise controlling strand *b* and the loop holding means for strand *a*;

Fig. 10 is a horizontal section on line 10—10, Fig. 9;

Fig. 11 is a vertical section taken just to the right of part 18a in Fig. 10; and

Fig. 12 is a sectional view of the bill of the knot tyer.

The following mechanism is or may be substantially the same as in the mentioned Klein application, to wit:

The ends of the strands forming the two

warps are held in a clamp 1 and are assumed to extend upwardly thereto from between the members 2—3 of a fork (itself not here shown or material) which projects toward the observer in Fig. 1 and to which they extend from their respective beams 4—5, being held tensioned by the clamp and beams. Prior to operations here material the two strands to be knotted together (the nearest two or the two appearing in the drawings) have been shifted forward toward the free ends of the fork and one transferred so that both engage member 2 (Fig. 2) and they cross each other with strand *a* forward of strand *b* and they are then carried forward by the fork and separated by a tapering point 6 on the hook 7 of the first loop-former pivoted at 8. The first loop-former now moves to the left and, its point 6 camming strand *a* rearwardly, its hook draws strand *b* to the left forward of strand *a*, forming loop *b*' around and a hitch with strand *a*. The knot-tyer, generally designated by 9 and pivoted at 10 and actuated by groove 11a of a rotating cam 11 and connected at 9a with the first loop-former to actuate the same as described, now descends between loop *b*' and the upreaching part of strand *a* (Fig. 3) whereupon, the strands being now held by the bill of the knot-tyer at the knotting point, fork member 2 withdraws; the bill of the knot-tyer is formed by two fixed members 9b and an intervening member 9c (Figs. 4 and 12) which is pivoted as shown and which coacts with one of these members first to grip and with the other then to sever the strand *a* in a way in itself known in the art (see Fig. 12, where the member 9c and one of the members 9b have rounded gripping edges and member 9c and the other member 9b have sharp severing edges), its motion being obtained from a groove 11b (Fig. 2) in the cam. The second loop-former 12, universally pivoted at 12a, now moves toward the observer against strand *a*, then down past the hitch in the strands and then rearward, catching strand *a* on a shoulder 9d of the knot-tyer and forming a loop *a*' therein (Fig. 4), whereupon it leaves one stretch of this loop in the bill of the knot-tyer, which now closes to grip and

then sever strand *a*, the bight formed in said strand around the bill and loop *b'* clearing the shoulder *9d* and slipping down off the bill so that the end of the portion of strand *a* which extends from beam 4 is drawn up through said bight, Fig. 8, and pulled to complete the knot as the knot-tyer now rises; the second loop-former obtains its forward and back movement from a lever 13 engaged with a peripheral groove 11c of cam 11 and its up and down movement is effected through a link 14 from a lever 15 engaged with cam-groove 11a.

We come now to the present improvements. Strand *b* must be cut in the upper stretch of its loop *b'* and both strands held under control as the knot-tyer withdraws.

The holding and severing of strand *b* is effected as follows: Fixed to an arm 16 secured to a part of the frame 17 of the apparatus is a blade 18. On the lever 13 is a crooked arm 13a to which are affixed two rearwardly projecting blades 19—20 with blade 18 between them. Blade 19 is slotted at *w* to receive a headed guiding stud 21 which keeps blades 18 and 19 face to face and blade 18 is slotted at *x* to receive a similar guiding stud 22. Blades 18—19 have rounded gripping edges at *y* and blades 18—20 shearing edges at *z*, these being so arranged that on the upper stretch of the loop *b'* of the thread *b* resting in the notch between the two pairs of edges *y*—*z* and blades 19—20 moving forward (to the left in Fig. 9) said upper stretch will be first gripped and then severed. Thus, when at the outset the strands *a*—*b* are shifted forward, and thereupon separated by point 6 of the first loop-former 7, as described, the horizontal stretch of strand *b* passes under the blades 18—19—20 at their rear ends in Fig. 1 (or their right hand ends in Fig. 9) and comes against a stop 18a on blade 18, after which the loop forming motion of loop-former 7 draws strand *b* over the blades and between their pairs of edges *y*—*z* (forming the loop *b'*) and then the blades are operated first to grip and then to sever the upper stretch of the loop, the gripped portion being that which extends to beam 4 and the grip being maintained till the knot is tied. This part of the mechanism is generally similar in construction and function to that of the said Klein application. We shall later advert to means for tensioning the upstanding stretch of strand *b* for a specific purpose.

Referring, now, to the means for controlling strand *a* as the knot-tyer withdraws: At the right of the frame 17 in Fig. 1 (see also Figs. 2 and 7) is secured a fixed blade 23 which has a rearwardly and upwardly inclined deflecting surface 23a terminating in a hook or gripping shoulder 23b; strand *a*, when the two strands are shifted forward at the outset as described, is deflected by surface 23a and caught by this shoulder. In wiping

contact with this blade 23 is a somewhat resilient blade 24 pivoted thereto and having a straight gripping edge or shoulder at 24a, between which and shoulder 23b thread *a* becomes lodged; the blade 23 is crooked at 24b to receive a lug 13x on lever 13, which is thus its actuating medium. Thus strand *a* will be gripped. Its release at the proper time is effected by a member 25 (Fig. 5) held against cam 11 by its own elasticity and when moved outward by the hump 11x on said cam pressing blade 24 from blade 23 so that the grip of the blades on strand *a* relaxes. In the mentioned Klein apparatus the gripping means for both strands operated in unison, their moving gripping members being in effect unitary. In the present construction they are separate and separately actuated, and it is possible to time their functions so as to favor the proper tying of the knot, as will appear.

In further reference to the control of strand *a*, and consequently of the knot-forming portions of both strands: In the bearing 17x (Fig. 9) of the frame 17 is fulcrumed a two-armed lever one arm 26 of which is held by a spring 26a against a cam 27 rotating with cam 11 and the other 28 carries a needle-like noose-holder 29 projectible in the movement of the lever to the left (Fig. 1) through an aperture 18b in fixed blade 18 so that it will lie in such position that when the loop *a'* of strand *a* is formed around loop *b'* of strand *b* said noose-holder will be embraced by loop *a'*; when the bill of the knot-tyer grips and then cuts this loop *a'*, leaving its cut-off portion hanging pendent, only a single stretch of the loop remains as the noose *a''* around loop *b'* and the loop-holder (Fig. 8).

Describing, now, the operation of the apparatus as refined by this invention as so far described:

The two strands (crossed as in Fig. 2) having been shifted forward so that strand *b* underlies its gripping and severing blades and is adjacent stop 18a and strand *a* engages shoulder 23b and loop *b'* having been formed by loop-former 7 in strand *b* and lever 13 having moved forward (causing the second loop former 12 to move forward preparatory to its downward movement to form loop *a'* in strand *a*) and later moving back (causing loop-former 12 to bring loop *a'* into the grip of the knot-tyer bill) in this backward movement it actuates blades 19—20 so that strand *b* is cut and gripped. Loop *a'* having by loop-former 12 been passed down across loop *b'* and thus positioned to cross also the noose-holder 29 and severed and the severed end held by the bill of the knot-tyer, leaving the loop *a'* across the loop and noose-holder, the knot-tyer rises somewhat and comes to a pause (Fig. 8). But in the described forming of loop *a'* (see Fig. 4) strand *a* underwent some increased tension and consequent

elongation or extension (being held fast at 1 and 5) and while thus additionally tensioned the mentioned backward motion of lever 13 acted to cause strand *a* to be gripped by 5 23—24, so that there is residual tension or stored-up elastic force in strand *a* to the right (Figs. 1 and 8) of these latter blades. This latter occurred before the bill, having gripped strand *a*, then rose, that is, with some 10 incidental slackening of the tension to the left of the means 23—24, and without the bill as yet drawing up the noose tight. On the bill coming to a pause the gripping means 23—24 releases strand *a* and the mentioned 15 residual tension therein now comes into play to draw up the noose of *a* around loop *b'* and the noose-holder 29, (the portion of strand *a* which reaches through the loop slipping therethrough to the right in Fig. 8), after 20 which the bill continues its upward movement to draw up the knot tight and the loop-holder withdraws. What we aim at by this is to avoid the bill causing the noose *a*² to slip off the free end of loop *b'*, which would mean 25 failure to tie the knot; a perfect knot by the present invention results partly because the noose-holder definitely fixes the tying point and thus contributes to prevent the noose slipping off the loop *b'* and partly because the 30 residual tension in thread *a* draws up the noose so as to sufficiently snugly embrace the loop to prevent its slipping off its free end when the movement of the knot-tyer to draw the noose tight occurs. The elasticity referred to is such as is present in almost any 35 fibrous strand; it will usually be present in both strands but of course if it is present in only strand *a* the invention would be accomplished.

40 When the fork 2—3 recedes and leaves the strand hitch held by the bill of the knot-tyer there occurs an undesired relaxation of the tension on the strands which tends to place them out of control and which we avoid by 45 interposing in the path of the loop *b'* as it is formed by loop-former 7 a take-up device in the form of a lever 30 urged normally toward the right in Fig. 1 by a spring 31. This is pressed back by said loop as it forms and 50 when the hitch slips off of the fork this device takes up any slack tending to form and maintains the desired tension.

Having thus fully described our invention what we claim is:

55 1. The method of tying a weaver's knot which consists in arranging two strands so that a loop is formed in one around the other and a noose is formed in said other strand around said loop and in embracing relation to a noose-holder and drawing the noose into constricting relation to both said loop and the noose-holder at once.

60 2. The method of tying a weaver's knot which consists in first forming a loop in one strand around another, then forming a noose

in the other strand around the loop and in position to embrace a noose-holder, and contracting the noose while it still embraces the loop and noose-holder.

3. The method of tying a weaver's knot 70 which consists in forming a loop in one strand around another, passing the portion of the other strand which extends in one direction from the loop around one side of the loop and between itself and the other side of the loop 75 to form a noose positioned to embrace a noose-holder, and then causing said other strand to slip through the loop in the direction in which its remaining portion extends from the loop and thereby contracting the 80 noose about the noose-holder and loop.

4. The method of tying a weaver's knot which consists in forming a loop in one strand around another, passing the portion of the other strand which extends in one direction 85 from the loop around one side of the loop and between itself and the other side of the loop to form a noose positioned to embrace a noose-holder, and then drawing the noose into constricting relation to both said loop and noose- 90 holder at once.

5. The method of tying a weaver's knot which consists in forming a loop in one strand around another, passing the portion of the other strand which extends in one direction 95 from the loop around one side of the loop and between itself and the other side of the loop and then causing said other strand to slip through the loop in the direction in which its remaining portion extends from the loop and thereby contracting the noose about the loop.

6. The method of tying a weaver's knot which consists in forming a loop in one strand around another, passing the portion of the other strand which extends in one direction 105 from the loop around one side of the loop and between itself and the other side of the loop, then causing said other strand to slip through the loop in the direction in which its remaining portion extends from the loop and thereby contracting the noose about the loop 110 and then drawing upon the first portion in the direction in which it extends from the loop.

7. The method of tying a weaver's knot in 115 two strands one of which is elastic which consists in holding the elastic strand at two spaced points, forming a loop in the other strand around the elastic strand between said points and, while causing the thus-engaged 120 strands to tension each other, passing a portion of the elastic strand between one of said points and the loop in a loop across one side of the first loop and thereby elongating and storing up elastic force in the elastic strand, 125 gripping the elastic strand between the first loop and the other of said points and thereby isolating the elastic force stored up in the elastic strand between said other point and the point of gripping from the remainder of 130

both strands and meanwhile passing said portion of the elastic strand between itself and the other side of the first loop and thereby forming a noose in the elastic strand around such first loop, and then relaxing the grip on the first strand and thereby permitting the elastic force to contract the noose.

8. The method of tying a weaver's knot in two strands one of which is elastic which 10 consists in holding the elastic strand at two spaced points, forming a loop in the other strand around the elastic strand between said points and, while causing the thus-engaged strands to tension each other, passing 15 a portion of the elastic strand between one of said points and the loop in a loop across one side of the first loop and thereby elongating and storing up elastic force in the elastic strand, gripping the elastic strand between 20 the first loop and the other of said points and thereby isolating the elastic force stored up in the elastic strand between said other point and the point of gripping from the remainder of both strands and meanwhile 25 passing said portion of the elastic strand between itself and the other side of the first loop and thereby forming a noose in the elastic strand around such first loop, then relaxing the grip on the first strand and thereby 30 permitting the elastic force to contract the noose, and finally pulling upon said portion of the elastic strand to cause the noose to constrict the loop.

9. A weaver's knot-forming mechanism 35 comprising, in combination, means to form in one of the two strands to be knotted together a loop around the other, means to form a noose in the second strand around said loop, a noose-holder positioned to be 40 embraced by the noose in the forming thereof, and means after the noose is formed to separate one from the other the noose and noose-holder.

10. A weaver's knot-forming mechanism 45 including means to hold two strands with one looped around the other and the latter extending around the loop and between itself and the loop in a noose and thereupon draw up said noose, a noose-holder movable into and out of position to be embraced by said noose when formed, and means to move the noose-holder into and out of said position.

11. A weaver's knot-forming mechanism 55 comprising, in combination, means to form in one of the two strands to be knotted together a loop around the other, means to form a noose in the second strand around said loop, a noose-holder movable into and 60 out of position to be embraced by the noose on the forming thereof, and means to move the noose-holder into and out of said position.

12. A weaver's knot-forming mechanism comprising, in combination, means to form 65 in one of the two strands to be knotted to-

gether a loop around the other, the latter strand being elastic, spaced means to maintain the elastic strand stretched, means to pass the portion of said elastic strand between the loop and one of said spaced means 70 across the loop and thereby store up elastic force in the elastic strand, means temporarily to hold the portion of the elastic strand between the loop and the other spaced means against relaxing, and means to pass the first portion between the loop and said elastic strand to thereby form a noose in the latter around the loop during the temporary holding of the second-named portion, whereby when said holding ceases the elastic force 80 stored up in the elastic strand will cause the latter to slip through the loop and constrict the noose.

13. A weaver's knot-forming mechanism comprising, in combination, means to form in one of the two strands to be knotted together a loop around the other, the latter strand being elastic, spaced means to maintain the elastic strand stretched, means to pass the portion of said elastic strand between the loop and one of said spaced means 85 across the loop and thereby store up elastic force in the elastic strand, means temporarily to hold the portion of the elastic strand between the loop and the other spaced means against relaxing, and means to pass the first portion between the loop and said elastic strand to thereby form a noose in the latter around the loop during the temporary holding of the 90 second-named portion, whereby when said holding ceases the elastic force stored up in the elastic strand will cause the latter to slip through the loop and constrict the noose and means, after said holding ceases, to draw upon said first portion to further constrict the noose.

14. In combination, a pair of strand-gripping blades movable one in wiping contact with the other, said blades having gripping portions coactive to grip a strand intersecting their planes when the movable blade is moved in one direction and one of said blades being resilient, and means upon the blades gripping a strand, to flex the resilient blade from the other out of its normal plane. 100

15. Strand-holding means comprising a pair of gripping blades one of which is movable in wiping contact with the other and thereby into strand-gripping relation to the other, one blade being elastic, and mechanism to cause such movement of the movable blade and thereupon bend the elastic blade from the other blade to relax the grip of the blades on the strand. 110

In testimony whereof we affix our signatures.

FREDERICK KLEIN.
FRED WALSLEBEN.
